UNITED STATES PATENT OFFICE

JOHN W. COPPAGE, OF FRANKLIN PARK, ILLINOIS

WHEEL-FLANGE LUBRICATOR

Application filed September 5, 1928. Serial No. 304,036.

This invention relates to new and useful improvements in wheel flange lubricators and aims to provide a novel, simple and efficiently operating lubricating device for the flanges of locomotive wheels.

By reason of the present invention a suitable lubricant is continuously applied to the flanges of locomotive wheels.

Other objects will become apparent as the nature of the invention is better understood, the same comprising the novel form, combination, and arrangement of parts hereinafter more fully described, shown in the accompanying drawing and claimed.

15 In the drawing wherein like reference characters indicate corresponding parts throughout the several views:

Figure 1 is a side elevation of my improved lubricator, the same being installed 20 in a locomotive wheel and locomotive frame member with which the device is attached fragmentarily illustrated,

Figure 2 is an enlarged detail section 25 through the casing of the attachment unit with which is pivotally associated the lubricant carrier,

Figure 3 is an outer side elevation of said lubricant carrier,

Figure 4 is an enlarged plan view of this 30 carrier, the cover plate thereof being removed,

Figure 5 is a detail longitudinal section through the said lubricant carrier,

Figure 6 is a plan view partly in cross 35 section of said attachment unit, and

Figure 7 is a perspective of the lubricant actuating lever.

Now having particular reference to the drawings A designates one of the wheels of 40 a railroad locomotive and B one of the frame members of the car above and slightly inwardly of said wheel.

The device per se consists of a casting 5 in the form of an attaching arm 6 having 45 a depending and inclined housing 7 formed upon its inner end. Said arm is provided with two or more openings 8 whereby to enable its being anchored to the top side of the locomotive frame member B as clearly illustrated in Figure 1.

This housing is somewhat conical shaped in longitudinal section open at its outer enlarged end, this end being inclined as disclosed in both Figures 1 and 2.

The top wall of this housing 7 is defined 55 by a hinged lid 9. Pivotcd within the inner end of this housing 7 as at 10 is an outwardly and downwardly extending arm 11 that projects through the open outer end of said housing, as clearly illustrated in Figure 2.

Cast integrally with the outer end of this 60 arm 11 is an inclined lubricant carrier 12. This carrier is in the form of a shallow casing 13 equipped with a hinged lid 14. The lower end of this casing is constructed with 65 a longitudinally extending trough 15 that is open at its lower end and within which is longitudinally movable a stick of lubricant 16.

The inner wall of this trough is provided 70 with a longitudinally extending slot 17 that terminates in spaced relation with the lower end of this trough, see Figure 4.

Arranged against the inner end of this 75 lubricant stick 16 is a follower member 18 to which is pivoted the inner end of a lubricant stick actuating lever 19 that extends upwardly into the casing 13 and adjacent the upper end wall of said casing.

Pivoted to the top wall of this casing 18 adjacent the end wall remote from the lever 19 80 is a link member 20 to the ends of which are attached upwardly extending and crossed retractile coil springs 21 and 22.

The opposite end of the spring 21 is anchored to the interior of the casing as at 23 while the opposite end of the other spring is attached to the lever 19 as at 24. Swinging movement of the link 20 in opposite directions is limited through the medium of stop pins 25-25 located at predetermined 85 points within the casing and beneath said links.

Pivoted to the back wall of the casing 13 adjacent the inner end thereof is a short arm 95 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

wardly of the channel 15 to maintain the same in positive engagement with the flange of the car wheel A as clearly illustrated in Figure 1.

In order to maintain a downward pressure upon the lubricant carrier 12 there is arranged through a slot in the outer end of the bottom wall of the housing 9 an elongated bolt 28 threaded at its inner end and extending through a slot 29 in the arm 11 of said lubricant housing.

Arranged upon the bolt above the arm is a washer 30 and passed around the bolt between the washer and the head is an expandable coil spring 31.

Threaded upon the bolt beneath the bottom wall of the housing 7 is an adjustment nut 32 whereby the tension of said spring 31 may be regulated. In order to limit the downward movement of the arm and said lubricant container there is threaded through an opening in the bottom wall of the housing 7, a machine screw 33 the inner end thereof adapted to bear within a pit or recess 34 in the adjacent surface of the lubricant container arm 11, see Figure 2.

It will thus be seen that I have provided a highly novel, simple, and efficient wheel flange lubricator that is well adapted for all the purposes heretofore designated.

Even though I have herein shown and described the invention as consisting of certain detail structural elements, it is nevertheless to be understood that minor changes may be made therein without affecting the spirit and scope of the appended claims.

Having thus described my invention, what I claim as new is:

1. In a wheel flange lubricator, an arm adapted to be secured to the stationary member of a car frame adjacent the wheels of a car, a housing formed integral with the arm at one end of the arm, the outer end of the housing being inclined and opened, an arm pivotally mounted within the housing and having its free end projecting through said opening, a stop member supported in one wall of the housing and adapted to be engaged by said arm to limit the movement of the arm in one direction, said arm being provided intermediate its ends with an opening, a bolt threaded in one wall of the housing and extending through the opening in said arm, a spring member disposed about the bolt, said spring impinging against the head of the bolt at one end of the spring and at its opposite end impinging against said arm for normally urging the arm against said stop member, a lubricant container supported on the free end of said arm, a follower member adapted for sliding movement longitudinally of the container for urging the lubricant outwardly of the container for application of the lubricant to the flange of the car wheel, a lever pivotally mounted intermediate its ends within the casing, means operatively connecting one

end of said lever with said follower member, spring means for normally urging the lever in one direction for actuating said follower to urge the lubricant exteriorly of its container.

2. A wheeled flange lubricator comprising a housing, means for supporting the housing above the wheel of a locomotive, said housing being provided with an open inclined end, an arm pivotally mounted within the housing, said arm having one end thereof extending through the open end of the housing for movement in the open end of said housing, spring means for normally urging the arm in a direction toward the wheel of the locomotive, a stop member arranged within the housing and adapted to be engaged by said arm for limiting the movement of the arm against the action of the spring, and an inclined container carried on said one end of the arm, said container having a trough in the bottom thereof extending longitudinally thereof, said trough being open at one end and having said open end disposed in operative relation with respect to the locomotive wheel, a stick of lubricant slidable in the trough, and a spring pressed follower located within the trough for movement longitudinally of the trough for urging the lubricant through the open end of the trough.

3. A wheel flange lubricator comprising a housing, means for rigidly supporting the housing above the wheel of the locomotive, said housing provided with an inclined open end; an arm pivotally mounted in said housing, said arm having the free end thereof movable in the open end of the housing, a container carried by said arm on said free end of the arm, said container disposed at an incline in operative relation to the locomotive wheel, said container having a trough formed therein, said trough having an open end disposed in operative relation to the car wheel, a stick of lubricant slidable in the trough, said trough having one wall thereof provided with a longitudinally extending slot, a lever pivotally mounted within said container, said lever having one end thereof movable in the slot, a follower member secured to said one end of the lever and adapted for movement longitudinally of the trough for urging the lubricant through the open end of said trough, and spring means within the container operatively associated with said lever for rocking said lever upon its pivotal connection in one direction for actuating said follower.

In testimony whereof I affix my signature.
JOHN W. COPPAGE.
